UNITED STATES PATENT OFFICE

FORREST C. GARRISON, OF CHICAGO, ILLINOIS, ASSIGNOR TO OSCAR C. RIXON CO., OF CHICAGO, ILLINOIS, A CORPORATION OF ILLINOIS

DESIGN FOR A THRESHOLD

Application filed March 17, 1930. Serial No. 34,909. Term of patent 14 years.

To all whom it may concern:

Be it known that I, FORREST C. GARRISON, a citizen of the United States, residing at Chicago, in the county of Cook and State of Illinois, have invented a new, original, and ornamental Design for a Threshold, of which the following is a specification, reference being had to the accompanying drawing, forming a part hereof.

The drawing is a perspective view of a section of a threshold embodying my new design.

I claim:

The ornamental design for a threshold substantially as shown.

FORREST C. GARRISON.
